UNITED STATES PATENT OFFICE.

ALFRED LEE KRONQUEST, OF CHICAGO, ILLINOIS, ASSIGNOR TO CONTINENTAL CAN COMPANY, INC., OF SYRACUSE, NEW YORK, A CORPORATION OF NEW YORK.

METHOD OF FORMING AND APPLYING RING-LINERS TO CAN ENDS.

1,372,961.

Specification of Letters Patent. Patented Mar. 29, 1921.

Application filed September 3, 1918. Serial No. 252,391.

To all whom it may concern:

Be it known that I, ALFRED LEE KRONQUEST, a citizen of the United States, residing at Chicago, in the county of Cook, State 5 of Illinois, have invented certain new and useful Improvements in Methods of Forming and Applying Ring-Liners to Can Ends, of which the following is a description, reference being had to the accompanying drawing and to the figures of reference marked 10 thereon.

The invention relates to new and useful improvements in the method of forming and applying ring liners to metal can ends, and 15 more particularly a paper ring liner to a can end having the peripheral edge thereof formed with a curl to facilitate the stacking of the can ends and the forming of the flange of the can end and the can body into a double seam.

An object of the invention is to provide a method of forming and applying ring liners to can ends, wherein the material of the can end is used as a coöperating element in the 25 forming of the ring liner.

A further object of the invention is to provide a method of forming and applying ring liners to can ends having the peripheral edge thereof curled, wherein the edge of the metal 30 of the can end is used as a coöperating element in the final cutting of the ring liner, so that the ring liner conforms in outline to the shape of the can end to which it is applied, and so that the ring liner may be applied to the can end simultaneously with the cutting thereof.

A further object of the invention is to provide a method of forming and applying ring liners to can ends, wherein the edge 40 of the can end subsequently rolled into a double seam is utilized in the final cutting of the ring liner, so that a failure to cut the material forming the ring liner at any point indicates that the curled flange is imperfect 45 and the can end may be rejected.

A still further object of the invention is to provide a method of forming and applying ring liners to can ends, wherein an adhesive material may be first applied to the 50 groove in the can end which receives the ring liner and in which the edge of the metal forming the curl on the can end is utilized in the final cutting of the ring liner, so that the coöperating means may seat the

liner in the groove in the can end and 55 against the adhesive material.

In the drawings:

Figure 1 is a view showing more or less diagrammatically and in vertical section, an apparatus for carrying out my method; 60

Fig. 2 is a view partly in plan and partly in section of the same;

Fig. 3 is a view partly in section and partly in side elevation centrally through the cutting station and at right angles to the 65 view shown in Fig. 1;

Fig. 4 is a view in perspective showing the final cutting of the paper strip and the seating of the finished ring liner in the groove in the can end; 70

Fig. 5 is a transverse sectional view showing the position of the parts just as the liner is first severed from the paper strip; and

Fig. 6 is a view showing the liner seated 75 in the groove in the can end.

The invention broadly is directed to a method of forming and applying ring liners to metal can ends, which can ends are formed with a curled edge to facilitate the stacking of the can ends and also to facilitate the 80 rolling of the edge of the can end and the flange on the can body into a double seam.

The ring liners are preferably made of paper, although any other suitable substance may be employed. The paper from 85 which the liner is to be cut is in strip form and is preferably presented to a cutting means which cuts out a disk and thus forms the inner edge of the ring liner. The paper strip is then placed relative to the can end, 90 so that the opening therein is concentric to the center of the can end. Means is then employed which coöperates with the material in the can end in the final cutting of the outer edge of the ring liner. This may 95 be accomplished by pressing the paper against the raw edge of the metal forming the curled edge of the can end. By pressing the paper against the edge of the metal, said metal edge serves as a cutting means operating to perform the final severing of the ring liner from the paper strip. This pressure is 100 preferably applied at one or more points and progressively from these points in a circumferential direction along the edge of the metal and may be applied by rolling balls along the surface of the paper, which balls are caused to press the paper against the

- edge of the metal, thus causing the cutting of the paper strip to form the ring liner. The cutting means not only severs the paper to finish the ring liner, but forces the cut 5 ring liner into the groove in the can end. The groove referred to is formed by an inner shoulder impressed in the metal forming the can end and the curled edge of the can end and is of the usual construction.
- 10 The inner diameter of the ring liner may be of such dimensions that the liner will frictionally engage the inner shoulder of the groove and hold the liner in place or the curled edge of the can end may operate to 15 hold the ring liner in place, but I prefer to use other means to insure the ring liner being held firmly against the bottom of the groove in the can end and insure the liner remaining attached to the cover even though 20 it be roughly handled, as, for example, the dropping of the same on the floor of the packing house. My preferred means consists in applying an adhesive material either to the metal at the bottom of the groove on 25 the can end or to the ring liner, so that the ring liner when placed in the groove will be held therein by the adhesive material.
- By my improved method of forming and applying ring liners to can ends, it will be 30 obvious that, if the edge of the metal forming the can end, has a cut out section or depression or is defective in any other manner, so that the can end when secured to the can body is liable to produce a leak, this defect 35 in the edge of the metal will prevent the complete severing of the material forming the ring liner, so that the defect is readily detected and the can end may be rejected.
- The invention will perhaps be made more 40 clear by reference to the accompanying drawings, which show more or less diagrammatically, an apparatus which may be utilized for carrying out my improved method.
- 45 The can ends are indicated at E in the drawings. These can ends are placed in a stack 1, carried by suitable frame-work and are adapted to be fed one at a time from the stack holder by means of a sliding bar 2, 50 which may be operated by a suitable lever 3 connected to the operating mechanism of the machine. The can ends are taken one at a time from the stack and by the first forward movement of the bar 2 will place the can end 55 at a station where adhesive material may be applied to the bottom of the groove in the can end at one or more points. The can end E' is indicated as at the station for applying the adhesive material. This may be ac- 60 complished by suitable brushes 4—4 carried by a cross-head 5, and these brushes are fed with a suitable liquid adhesive material by nozzles 6—6. The can ends receive a drop of liquid adhesive at each point directly be- 65 neath the brushes. The reciprocating bar 2 is formed with a yielding dog 7, which engages the can end at the stack and carries it to the position underneath the brushes. The table or support along which the can ends move is provided with detaining clips 8—8, 70 which hold the can ends in proper position beneath the brushes and prevent the return of the can end with the bar when it moves back to engage and bring forward another can end. On this backward movement of the 75 bar a second yielding dog 9 engages the can end indicated at E' in Fig. 3, and moves the same forward to the position indicated at E², which is directly over a vertically reciprocating supporting plunger 10. This 80 plunger is carried by a stem 11, which slides in the frame and said supporting plunger may be moved up and down by a lever 12, operated by a cam 13 on the shaft 14.
- The strip of material from which the ring 85 liners are made is indicated at P in the drawings. Said strip of material is fed intermittently by feed rolls 14', which are operated in any suitable way. The strip of material first passes beneath a die which 90 cuts a disk from the paper forming the inner edge of the ring liner. This die is indicated in Fig. 1, at 15. Said die is carried by a suitable reciprocating plunger 16, 95 operated by a lever 17, and a spring 18. Coöoperating with the die 15 is a second sleeve die 19. The disks as they are cut from the strip of paper pass down through the sleeve die 19 and will be stacked one 100 upon the other and this greatly facilitates the handling of the paper disks. The paper strip P is then fed forward by the feeding rolls 14' over the plunger support 10 and the can end E² thereon and the center of the opening formed in the paper strip is brought 105 into exact registration with the center of the can end. The can end is held in a pre-determined position on this plunger support by spring retaining fingers 20, see Fig. 2. Directly above the plunger support 10 is a 110 rotating head 21, which is provided with a series of balls 22. These balls are supported on the head so that they may rotate freely. As shown in Fig. 2 of the drawings, I prefer to use four balls. After the paper strip 115 is brought into register with the can end the plunger support 10 is raised, so that the paper strip is brought against the sharp metal edge formed by the curl e in the can end E. As the head rotates the balls are 120 pressed against the paper strip and the pressure of the ball forces the strip against the sharp metal edge of the can end and this pressure shifts with the movement of the ball along the peripheral edge of the can end. The pressure of the ball against the paper strip and the paper strip against the edge of the metal causes the metal edge to 125 sever the paper and thus forms the outer edge of the ring liner, which, of course, 130

finishes the ring liner. The position of the ball and the diameter of the same is such as not only to cause a cutting of the paper strip to form the ring liner, but the ball places 5 the cut ring liner in the groove in the can end. This groove in the can end is formed by the shoulder e' which is impressed in the cover and the outer curled edge. The groove is of the usual construction. The 10 edge is curled in the usual manner to facilitate the stacking of the can ends and to facilitate the rolling of the can end and flange on the can body into a double seam. The ring liner as it is seated in the groove 15 comes into contact with the adhesive material and will be firmly held in the groove, so that the ring liner will not be dislodged therefrom even by the rough handling of the cover—as the dropping of the same upon 20 the floor of the packing house.

After the liner has been formed and placed in the groove in the can end, the plunger support then drops and the paper strip is again fed forward another step. 25 If the edge of the metal is cut out or depressed or is in any other way defective, then the paper strip would not be cut at the point where the defect occurs and the ring liner clinging to the paper strip enables the 30 operator to readily detect the imperfect can end, so that it may be rejected. The ring liner is indicated at P' in the drawings.

It will be understood that the apparatus described above may be changed in many respects, and at the most is only one way of carrying out my improved method, which consists broadly in utilizing the metal of the can end as a co-operating element in the final cutting of the ring liner and the applying of the ring liner to a can end at the 40 station and at the time when said ring liner is cut.

Having thus described my invention, what I claim as new and desire to secure by Letters Patent, is:

1. The method of forming and applying paper liners to a metal can end having a

laterally projecting flange which consists in placing the strip of paper against the edge of the can end, and pressing the strip 50 against the edge of the metal forming the flange at one or more points, and progressively shifting the pressure from said point or points along the edge of the metal for severing the paper from the strip. 55

2. The method of forming and applying ring liners to metal can ends, which consists in cutting a paper strip to form the inner edge of the ring liner, placing the strip with the center of the opening thus formed in 60 register with the center of a can end having its edge curled, and pressing the paper strip against the edge of the metal forming the curl to sever the same, thus forming the outer edge of said liner. 65

3. The method of forming and applying ring liners to metal can ends, which consists in cutting a paper strip to form the inner edge of the ring liner, placing the strip with the center of the opening thus formed in 70 register with the center of a can end having its edge curled, pressing the paper strip against the edge of the metal forming the curl to sever the same, thus forming the outer edge of said liner, and utilizing the 75 pressing means for seating the finished liner on the can end.

4. The method of forming and applying ring liners to metal can ends, which consists in placing a paper strip over the inner face 80 of a can end having its edge curled, pressing the paper strip against the edge of the metal forming the curl at one or more points and progressively shifting the pressure from said point or points along the edge of the 85 metal for severing the paper from the paper strip to form the ring liner.

In testimony whereof, I affix my signature in the presence of two witnesses.

ALFRED LEE KRONQUEST.
